FIG.1

FIG.4

FIG.5

FIG.3

FIG.2

FIG. 1 is a side view in perspective of a dryer hood showing our new design;

FIG. 2 is a top plan view thereof on a reduced scale;

FIG. 3 is a rear perspective view thereof;

FIG. 4 is an enlarged fragmentary sectional view taken on line 4—4 in FIG. 1; and

FIG. 5 is an enlarged fragmentary sectional view taken on line 5—5 in FIG. 2.

The characteristic feature of our design resides in the combination on the double domed transparent hair dryer hood of the opaque band spaced from the lower edge together with the outwardly flared perforations on the inner dome above the band, presenting a scintillating effect, all as shown.

We claim:

The ornamental design for a dryer hood, as shown and described.
